5 Claims. (Cl. 74—6)

This invention relates to a device for effecting axial shifting of the driving pinion unit in an engine starter drive, of the type comprising a fork acting on a shifting member mounted for rotation and axial displacement against the action of a spring on a helically splined sleeve which fits on a helically splined end of the shaft of the engine starter and is coupled through an overrunning clutch or a free wheel with the pinion arranged to engage the gear on the flywheel of the internal combustion engine.

The object of this invention is to provide a shifting member for turning gears of the type referred to above, wherein said member is of simple construction and comprises punched components only, which do not require any further machining and can be easily assembled.

With the above and further objects in view, which will appear from the appended description this invention provides a turning gear for effecting axial displacement of the driving pinion unit for engine starter drives of the type referred to above, wherein the shifting member interposed between the actuating fork and sleeve slidably splined to the end of the engine starter shaft, comprise two sheet metal discs slidably and rotatably mounted on the sleeve, said discs being interconnected by means of tabs and notches, so as to define therebetween an annular groove in which a third disc is loosely mounted, the latter disc being acted upon by the limbs of the actuating fork, the fork cooperating with said third disc to keep it against rotation.

The invention shall be described in detail with reference to the accompanying drawings showing embodiments thereof, and wherein:

FIGURE 1 is a side elevational view of a turning gear according to this invention,

FIGURE 2 is an axial view thereof,

FIGURE 3 is a part sectional view on line III—III of FIGURE 2,

FIGURE 4 is an exploded perspective view of the shifting member,

FIGURE 5 is an axial sectional view of another embodiment of the shifting member,

FIGURE 6 is an axial view of a further modification of FIGURE 2,

FIGURE 7 is a cross sectional view on line VII—VII of FIGURE 6, and

FIGURE 8 is a part sectional view on line VIII—VIII of FIGURE 6.

In the embodiment shown in FIGURES 1 to 4 a fork 7 fast with a control lever, is pivoted on a pivot 8 and operated in a known manner by an electromagnet or a pull rod, not shown.

The fork 7 acts on a shifting member generally denoted by 11, mounted for rotation and axial displacement against the action of a spring 5 on a helically splined sleeve 6 mounted on an end of the shaft 12 provided with corresponding splines 14 of the starting motor and coupled through a free wheel 10 with a pinion 9 arranged to engage the gear on the flywheel (not shown) of the internal combustion engine.

The shifting member 11 is actuated by the fork 7, and comprises a punched sheet metal disc 2 rotatably mounted

2

in a circular groove formed by two further punched sheet metal discs 1, 3 coupled together.

The disc 2 is in the form of a circular ring provided with two radial fingers 2a protruding from the outer edge 5 at diametrically opposite positions, engaged in corresponding slots 7b formed in two limbs 7a of the actuating fork 7 so that the disc 2 cannot rotate during operation of the engine starter and disengage from the fork 7.

The member on which the disc 2 is mounted comprises 10 a circular ring 1 formed with four circumferential radial notches 1a, and a disc 3 formed with a pressed boss so as to present two concentric circular rings 3a, 3c arranged on planes extending parallel with each other, spaced by a cylindrical section 3d integral therewith. The disc 3 is provided with four axial rectangular tabs 3b punched and bent from the inner edge of the smaller circular ring 3c.

On assembly the disc 2 is fitted on the cylindrical section 3d of the disc 3, whereupon the disc 1 is coupled with 20 the disc 3 and secured to the latter by inserting the tabs 3b into the notches 10 and bending them over. The two discs 1 and 3 are thereby spaced by the cylindrical section 3d so that they leave an annular groove therebetween in which the disc 2 is rotatably mounted.

25 The shifting member 11 is mounted on the sleeve 6 and the fingers 2a are fitted into the slots 7b of the fork 7.

The member 11 is prevented from slipping off the sleeve 6 by a stop member 4 comprising a resilient retaining ring of circular or rectangular cross-section engaged by an 30 annular groove in the sleeve.

35 FIGURE 5 shows a modification wherein both discs 1 and 3 are provided with cylindrical bosses 1b, 3d, respectively, and radial coupling faces 1c, 3c, respectively. The discs are interconnected, similarly to the previously described construction, by means of tabs and notches provided in the faces 1c, 3c.

FIGURES 6, 7 and 8 show a further modification in which the disc 2 is deprived of radial fingers indicated by 40 2a in FIGURE 4. The fork 7 is now provided at the end of its limbs 7a with ears 7c bent to U-shape to engage from opposite sides the circumferential edge of the disc 2. In order to prevent the rotation of the disc 2 when the starter operates and a consequent wear of ears 7c the disc 2 is formed with an axial projection 13 on its circumference.

45 The components of the shifting member 11 can be surface hardened in order to reduce wear from relative rotation.

In operation, the shifting member 11 is axially moved 50 by the fork 7 and by compressing the spring 5 moves the pinion 9 into engagement with the teeth on the engine flywheel, not shown. Upon engagement the engine starter is energized in a known manner, whereby the pinion 9, the free wheel 10, the sleeve 6, and the compression spring 5 rotate. Due to the spring reaction, the discs 3 and 1 of the member 11 also rotate, while, the disc 2 is held against rotation either by the fingers 2a engaged in the slots 7b of the fork 7 (FIGS. 1 to 4) or by the projection 13 abutting against one of the ears 7c (FIGS. 6 and 8).

60 What I claim is:

1. Turning gear for internal combustion engines for effecting axial displacement of the engine starter drive, of the type comprising a fork acting on a shifting member mounted for rotation and axial displacement against the action of a spring on a sleeve slidably by helical splining on the end of the engine starter shaft and coupled through a free wheel with the pinion engaging the engine gear on the flywheel of the internal combustion engine, wherein the shifting member interposed between the actuating fork and the sleeve comprises two sheet metal discs freely mounted on the sleeve and interconnected by

tabs and notches to define therebetween an annular groove in which a third sheet metal disc is loosely mounted, and connecting means for connecting said third disc to the actuating fork.

2. Turning gear as claimed in claim 1, wherein the two interconnected discs mounted on the sleeve are spaced by a cylindrical boss fast with one of the discs and forming the bottom of the annular groove.

3. Turning gear as claimed in claim 1 wherein said third disc is in the form of a flat circular ring and said connecting means comprises two diametrically opposite radially extending fingers secured to the circumference of said ring and a slot formed in the end of each limb of said actuating fork into which said fingers project.

4. Turning gear as claimed in claim 1 wherein the third

disc is in the form of a flat circular ring and said connecting means comprises said actuating fork formed with U-shaped radially directed projections on the limbs of the actuating fork adapted to embrace said third disc.

5. Turning gear as claimed in claim 4 wherein said third disc is provided with an axially directed abutment on one face thereof adapted to cooperate with said projections to limit relative rotation between said third disc and said fork.
